DES. 2279

J. P. C. Cambridge, Jr. of Enfield, N.H.

Letter Patent no 2279 Dated Mar. 10th 1866

Design for a Bedstead

The schedule referred to in these Letter Patent and making part of the same.

To all whom it may concern:

Be it known that I, J. P. C. Cambridge, Jr. of Enfield in the County of Grafton and State of New Hampshire have originated and produced a new design for a Bedstead of which the following is a full and clear description, reference being had to the accompanying drawings making part of this specification.

The design is intended for the ornamentation of the head and foot boards of bedsteads and particularly to the inner face of the former and the outer face of the latter, and the design consists in the general configuration of the top of these pieces, each surmounted by a curvilinear moulding the opposite ends of which curve over to join the corner posts as seen in the main figure of the drawing, which represents an end view of the bedstead, showing the ornamental parts of the head and foot boards in elevation.

The other figure shows an edge view of one of the upper posts, with the moulding springing therefrom.

a, denotes the head board, and b, the foot board, c, d, the mouldings surmounting the same and springing from the posts e, e, and f, f,

I claim the ornamental design or configuration for a bedstead, substantially as shown in the drawings.

In witness whereof I have hereunto set my hand this seventh day of February A.D. 1866.

J. P. C. Cambridge Jr.

E. T. C.
